DESIGN FOR A CLOTHES STICK

Julia T. Burg, Detroit, Mich.

Application April 10, 1944, Serial No. 113,202

Term of patent 7 years

(Cl. D49—1)

To all whom it may concern:

Be it known that I, Julia T. Burg, a citizen of the United States of America, residing at Detroit, in the county of Wayne and State of Michigan, have invented a new, original, and ornamental Design for a Clothes Stick, of which the following is a specification, reference being had to the accompanying drawing, forming a part thereof, in which Figure 1 is a perspective view of a clothes stick embodying my new design; Figure 2 is an end view thereof; and Figure 3 is a top plan view thereof with handle shown broken away for convenience of illustration.

I claim:

The ornamental design for a clothes stick, substantially as shown.

JULIA T. BURG.
